UNITED STATES PATENT OFFICE.

JESSE ADLER, OF NEW YORK, N. Y.

DESIGN FOR A STORE-FRONT.

56406.

Specification for Design.

Patented Oct. 26, 1920.

Application filed July 9, 1920. Serial No. 395,157. Term of patent 7 years.

To all whom it may concern:

Be it known that I, JESSE ADLER, a citizen of the United States, residing at New York city, in the county of New York and State of New York, have invented a new, original, and ornamental Design for Store-Fronts, of which the following is a specification, reference being had to the accompanying drawing, forming part thereof.

The figure is a front elevation of a store front, showing my new design.

I claim:

An ornamental design for a store front, as shown.

JESSE ADLER.
